UNITED STATES PATENT OFFICE.

MATTHEW LECHNER, OF NEW YORK, N. Y.

ELECTRIC STORAGE BATTERY.

Original No. 1,359,259, dated November 16, 1920, Serial No. 247,111, filed July 29, 1918. Application for reissue filed August 31, 1921. Serial No. 497,378.

To all whom it may concern:

Be it known that I, MATTHEW LECHNER, a citizen of the United States, and resident of the borough of Manhattan, city, county, 5 and State of New York, have invented certain new and useful Improvements in Electric Storage Batteries, of which the following is a specification.

My invention relates to electric storage 10 batteries, and more particularly to that type thereof in which lead plates form elements of the construction. In the operation of such batteries, a certain amount of material is cast off from the plates and passes down 15 to the bottom of the cells where it forms gradually increasing heaps of sediment which form connections between two plates of different polarity. The sediment comprises lead, lead peroxide and sulfate of 20 either, and it is true, is not a good conductor of electricity; it is, however, a sufficiently good conductor to establish an electrical circuit between adjacent positive and negative plates. Numerous small currents result, the 25 sum total of which represents a continuous and injurious loss of electrical energy at all stages and during the entire life of the battery.

The particular object of my invention is 30 to provide a construction in which these objectionable circuits between positive and negative plates, due to the accumulating sediment, are prevented and the consequent loss of electrical energy avoided.

35 Other more specific objects will appear from the description hereinafter, and the features of novelty will be pointed out in the appended claims.

In the accompanying drawings which, 40 for illustrative and descriptive purposes, show a number of examples of my invention, Fig. 1 is a longitudinal section of a portion of a battery cell showing one form of my invention; Fig. 2 is a cross-section 45 thereof on the line 2-2 of Fig. 1; Figs. 3, 4 and 5 are views similar to Fig. 1 showing additional forms of my invention; Figs. 6, 7 and 8 are perspective views of still other forms of my invention; Fig. 9 is a 50 plan view illustrating the form shown in Fig. 8; Fig. 10 is a sectional view showing a still further form of my invention and Fig. 11 is a cross-section thereof on the line 11-11 of Fig. 10.

As shown in the drawings, the battery 55 cell comprises the customary jar 15 of hard rubber or other suitable material, having a plurality of interiorly located ribs or bridges, for instance two, 16 and 16^a, projecting upwardly from its bottom. The 60 cell includes further the usual positive plates 17 and negative plates 18 supported in any well known way and spaced apart by separators 19 and 20 usually consisting of rubber and wood respectively. The 65 separators 19 and 20 are located in surface engagement with each other between two plates, with the rubber separator 19 in surface contact with the positive plate 17 and the wood separator 20 in surface engagement with the negative plate 18. The separators 19 and 20, when combined in pairs, are of such combined dimensions as to fit snugly between a pair of plates 17 and 18, and to frictionally engage the opposed surfaces thereof in the usual way; all of the 70 plates in a single cell, together with their supports, are thus secured together in the form of a unit in which the individual plates are incapable of relative movement 75 in any direction.

In the operative condition of the battery, the units comprising the positive plates 17 and negative plates 18 with their supports, and the separators 19 and 20, all in fixed 80 relation to each other are located within the jar 15 and rest upon the ribs or bridges 16 and 16^a in transverse relation thereto. It is a well recognized fact that the sediment 85 which falls from the plates in the operation of the battery, accumulates at the bottom of the jar, in heaps along the side surfaces of the ribs or bridges 16 and 16^a, the accumulation being greatest at these points and becoming gradually less toward the 90 centres of the spaces between plates. If, as in existing constructions, the lower edges of each plate 17 and 18 rest upon both bridges 16 and 16^a, short-circuiting of the 95 plates will occur as soon as the sediment therefrom reaches an amount sufficient to contact with a positive and a negative plate and thus establish an electrical connection therebetween. This occurs at a relatively 100 early stage in the use of the cell, since the falling sediment forms a skin on the bridges and the bottom of the jar, which skin is capable of electrically connecting the plates.

This objection is avoided in the form shown in Figs. 1 and 2 by making the lower edges 17^a and 18^a of the positive and negative plates 17 and 18 respectively, inclined 5 instead of at right angles to the vertical edges of said plates. In assembling the plates they are set in reversed relation to each other so that the edge 17^a inclines upwardly in one direction while the edge 18^a 10 inclines upwardly in the opposite direction; in other words, looking at the assembled plates as in Fig. 1 the edges 17^a and 18^a intersect each other. With the described arrangement the edge 17^a will rest upon the 15 bridge 16 and be free or spaced from the bridge 16^a while the edge 18^a will rest upon the bridge 16^a and be free or spaced from the bridge 16; owing to the fact that the plates are combined in the form of a rigid 20 unit with the separators 19 and 20 an efficient and adequate support of the battery elements is secured even though the plates alternately engage only individual bridges.

It will be obvious that the sediment 25 which always accumulates to the greatest extent along and upon the surfaces of the bridges 16 and 16^a cannot form a connection between a positive plate and an adjacent negative plate for the reason that one of 30 said plates is spaced from a given bridge. The top edges of the bridges 16 and 16^a are generally rounded or otherwise formed to prevent an accumulation of sediment thereon; the vibration resulting from a moving vehicle will also prevent the gathering of sediment in any material quantities upon the upper edges of the bridges.

In the form shown in Fig. 3 the lower edges of the plates 17 and 18 instead of 40 extending from one side edge to the other in a continuous incline are formed with compound inclines 17^b and 17^c and 18^b and 18^c; the inclines 17^c and 18^c are shorter than the inclines 17^b and 18^b with the proportions 45 so arranged that the junction points of the respective inclines represent the points at which the plates engage the bridges and upon which they are supported. The plates 17 and 18 in this form also, are set in reversed relation to each other so far as the inclined lower edges are concerned, so that the positive plates will be in engagement with and supported upon, for instance, the bridge 16 and spaced from the bridge 16^a 55 while the negative plates will be in engagement with and supported upon the bridge 16^a but spaced from the bridge 16 or vice versa.

As illustrated in Fig. 4, the plates 17 and 60 18 are symmetrical and the lower edges thereof are provided with lugs or projections 17^e and 18^e respectively located, when the plates are in reversed relation to each other, so as to register with the bridges 16 and 16^a. Thus the lugs 17^e of the positive

plates 17 will engage the bridge 16 and the lugs 18^e of the negative plates 18 will engage the bridge 16^a, the plates being each spaced from the other bridge.

In Fig. 5 the plates are also symmetrical 70 and at the lower edges are provided with notches 17^d and 18^d respectively arranged to register with the bridges 16 and 16^a; by assembling the plates 17 and 18 in alternate reversed relation to each other the notches 17^d will be in registry with one bridge, for instance, 16^a, while the notches 18^d are in registry with the other bridge 16. With this arrangement also each plate, positive and negative, rests upon one bridge only and is 80 out of engagement with the other; the points of engagement of the positive and negative plates are never with the same bridge and are never contiguous to each other.

Figs. 6, 7 and 8 illustrate my improvement applied to the bridges 16 and 16^a which as shown are provided with seats 16^b and recesses 16^c alternating with each other in each bridge; the arrangement is such that the seats 16^b and recesses 16^c of one bridge 90 will be staggered with respect to the seats and recesses of the other bridge or, in other words, the seats 16^b of the bridge 16 will register with the recesses of the bridge 16^a and vice versa. The plates 17 and 18 in this 95 case are symmetrical and of true rectangular form as in existing batteries; when in position in the cell the positive plates 17 will rest, for instance, upon the seats 16^b of the bridge 16^a and project over the recesses 16^c of the bridge 16 while the negative plates 18 will rest upon the seats 16^b of the bridge 16 and extend over the recesses 16^c of the bridge 16^a as shown in Fig. 9, in which the 100 separators 19 and 20 are shown as partly 105 broken away. It will be seen in this form that the plates are in contact with one bridge and out of contact with the others.

The form shown in Fig. 10 includes a central bridge 16^a and two outside bridges 110 16; the bridges 16 may be recessed as in Figs. 6, 7 and 8 or constructed as in the other forms. In this instance one set of plates, for instance, the positive plates 17, rests upon the seats 16^b of the bridges 16 115 and are provided with recesses 17^e in registry with the central bridge 16^a and of sufficient dimensions to escape contact therewith; the plates 17 thus straddle the central bridge but do not engage the same. The 120 negative plates 18 rest upon the central bridge 16^a but extend over the recesses 16^c of the outer bridges 16 and thus do not engage said outer bridges 16 as shown in Fig. 11. This form includes the same advantages as the other forms; even if the sediment should accumulate in sufficient quantities along the bridges 16 to form a connection between two negative plates 18 or along the central bridge 16^a to form a con- 125 130

nnection between two positive plates this will have no injurious results as in each case the connected plates are of the same polarity.

In all of the forms described the close frictional engagement between the plates, separators and other elements prevent either one of the groups of connected plates of the same polarity, or at least one set of the battery plates, from tilting on the single points of support as fulcrums into contact with the second bridge; the unit constituting the plates, separators, etc., is thus rigidly supported in proper position to maintain the upright edges of the plates, at all parts thereof, out of contact with the inner wall of the jar or container 15 and also to maintain the plates out of contact with a given bridge as desired. If through use or from other causes the group of plates of a given polarity should become loosened and thus be capable of independent movement relatively to the other group, any suitable means may be used to counteract or correct this condition; for instance, a suitable member of insulating material constructed in the form of a spacing device may be fitted between the plates near their upper portions for this purpose.

My improvements in all forms are extremely simple and efficient and may readily be combined in and with batteries of existing constructions. My improvements reduce the period of charging the batteries and avoid the necessity for forcing a surplus amount of electrical energy beyond what would ordinarily be required into the cell sufficient to keep the elements clean; in other words in existing constructions it is necessary to overcharge the battery to an extent corresponding with the amount of energy lost through the accumulating sediment. Naturally the energy at the disposal of the user, after the battery has been charged, is decreased to a like extent for the same reasons. My improvements also do away with practically all of the so-called self-discharge, obviate undue sulfating of the plates and the consequent necessity for overcharging to again clean the same, reduce the exposure of the plates to gassing to a minimum and increase the life of the batteries to a maximum extent by reducing the loosening and dropping of active material to very small amounts.

Various changes in the specific forms shown and described may be made within the scope of the claims without departing from the spirit of my invention.

I claim:

1. In a storage battery cell, the combination of a container, positive and negative plates therein said plates being combined in the form of a unit and having their upright edges, at all points, out of contact with the inner wall of the container, and spaced bridge elements in said container whereby said unit is supported in position, the supporting edges of the plates of at least one set having no more than a single point of contact with one of said bridge elements and being spaced from the other bridge elements that support other plates.

2. In a storage battery cell, the combination of a container, positive and negative plates therein, spaced bridge elements beneath said plates for maintaining them in position, the arrangement including recesses of minor dimensions with respect to the supporting edges of said plates, said recesses being located to correspond with the position of all the bridge elements save one so as to just span each of the bridge elements save one without allowing contact of that plate with the spanned bridge elements, the recessed plates being thereby supported by engagement with only one of the bridge elements and out of engagement with the other bridge elements that support the other plates.

3. In a storage battery cell, the combination of a container, positive and negative plates therein, said plates being combined in the form of a unit and having their upright edges, at all points, out of contact with the inner wall of said container, and spaced bridge elements in said container whereby said unit is maintained in position, the positive plate having a recess in registry with one bridge and the negative plate having a recess in registry with the other bridge, one of said sets of plates, at least, having contact with only one bridge but not with any other, said recesses being of minor dimensions with respect to the supporting edges of said plates.

In testimony whereof I have hereto set my hand this 27th day of August 1921.

MATTHEW LECHNER.
